UNITED STATES PATENT OFFICE.

ARTHUR LOW PATTERSON, OF ALBEMARLE, NORTH CAROLINA.

DENTAL FLOSS HOLDER.

Application filed December 16, 1922. Serial No. 607,363.

To all whom it may concern:

Be it known that I, ARTHUR L. PATTERSON, a citizen of the United States, residing at Albemarle, in the county of Stanly and State of North Carolina, have invented new and useful Improvements in Dental Floss Holders, of which the following is a specification.

This invention relates to improvements in 10 dental floss holders.

The object is to provide an appliance for removing foreign matter or particles of food from between the teeth by the use of a strand of some fibrous material such as dental floss held in a taut condition, and adapted to be passed between the teeth without interference to supplant the more or less injurious wooden tooth pick.

A further object is to provide a simple, 20 compact and cheaply manufactured device for holding a spool of such thread or floss, the said spool being entirely encased by a coacting receptacle and cover therefor, to maintain the floss in sanitary condition, the 25 casing and cover having means for preventing excessive unwinding of the floss.

Another object is to provide a casing for 30 this purpose which has means carried thereby for stretching the active portion of the strand, and means for effectively and quickly 35 fastening the ends of such portion, said means being in the form of spring cleats or clamps about which the strand may be easily wound and as readily unwound, to be engaged with a handy cutting device arranged 40 conveniently to sever the used portion of the strand, the entire device being small and light to be carried in the pocket while protecting the spool of floss.

A full and complete understanding of the 45 invention may be obtained from a consideration of the following detailed description, taken in connection with the accompanying drawing forming a part of this specification; 50 it being understood that while the drawing shows a practical form of the invention, the latter is not to be confined to strict conformity with the showing thereof, but may be changed or modified, so long as such 55 changes or modifications mark no material departure from the salient features of the invention, as specifically pointed out in the appended claims.

In the drawing, in which similar reference characters designate corresponding parts throughout the several figures:—

Figure 1 is a side elevation of the improved dental floss holder shown ready for use;

Figure 2 is a top plan view of the same; 60

Figure 3 is a rear elevation, partly broken away;

Figure 4 is a vertical sectional view taken on the line 4—4 of Figure 3 and looking in the direction indicated by the arrow; 65

Figure 5 is a detail elevation, partly in section, illustrating the manner of fastening the ends of the strand of floss;

Figure 6 is a detail sectional view taken on the line 6—6 of Figure 1; 70

Figure 7 is a detail sectional view taken on the line 7—7 of Figure 1.

The cylindrical box drum or casing for holding the spool of floss comprises a circular base or back 1 of circular form and composed 75 of some suitable, thin sheet metal having a peripheral, outstanding flange or rim 2, formed integrally therewith. To the outer or back side of the base 1 is secured the circular body portion 3 of a floss-supporting 80 arm 4 formed integrally therewith of similar sheet metal, the body portion being of substantially the same diameter as the base of the drum and secured rigidly thereto by means of one or more rivets 5. 85

Adjacent to the periphery of the drum, the body portion 3 is provided with an outstanding extension 6, whose outer face is tangential to the periphery of the drum and is perpendicular to the normally upper edge of the arm 4, which latter extends outwardly and radially to the center of the drum, the outer end of the latter having an outstanding extension 7, the terminal of which is in horizontal alinement with the end of the first-named extension 6. A reinforcing rib or flange 8, beginning at the extension 6, extends entirely around the body portion 3, the lower side of the arm 4 and the outer edge of the outer extension 7 as clearly 100 shown in Figure 1 of the drawing, said reinforcement being formed by returning the sheet metal back upon itself to strengthen the plate and prevent buckling the same.

In addition to the rivet 5, the base or back 105 1 and the body portion 3 of the attached

plate, are further held together by a centrally arranged post or pivot 9, which may be soldered or otherwise secured to both members, the length of the post being somewhat less than the depth of the peripheral flange 2, and upon this post 9 is adapted to be placed a spool 10, having a length of dental floss 11 or other fibrous material or strand wound thereon, the said spool preferably having a tubular bushing 12 mounted therein, the outer ends of the latter being formed into flanges to prevent its removal from the spool, as clearly shown in Figure 4 of the drawing.

15 A circular cover 13 formed of similar sheet metal and having a peripheral flange 14 of a diameter to slip over the receptacle or holder flange 2 is adapted to be frictionally held thereon, the center of the circular cover 13 carrying a pin 15 which enters the outer end of the bushing 12 and serves, in conjunction with the post 9, to act as a pivot for the spool of floss.

The inner flange 2 is provided with an 25 aperture 16 adjacent to the extension 6, and the flange 14 of the cover is likewise provided with an aperture 17, and the free end of the floss 11 is adapted to be passed through these apertures when the same are 30 alined by turning the cover on the receptacle, after which said cover may be turned sufficiently to cause a small portion of the length of floss to lie between the two flanges 2 and 14 respectively, which serves to hold 35 the floss wound upon the drum in taut condition, the frictional engagement of the bushing 12 on the alined pins 9 and 15 being sufficient to maintain such taut condition of the floss.

40 The extensions 6 and 7 are provided on their faces opposite to the drum and cover, with oppositely disposed cleats or clamps 18, formed by providing extended portions on the opposed edges thereof and bending 45 the same backwardly in opposite directions, to lie in spaced relation to the adjacent faces of the said extensions, as clearly shown in Figure 6, the upper and lower ends of said clamps being rounded and flared outwardly 50 to provide tongues 19 which project beyond the joining portions 20.

The extension 6 and the cleat or clamp 18 formed thereon, are each provided with an aperture 21, in alinement with each other, 55 and the end portion of the strand 11 of floss where leading from the aperture 17 is passed through said alined apertures 21 and is brought around the lower tongue 19, thence upwardly to be clamped by the cleat 18, and 60 thence across the space to the opposite or outer cleat 18, where the strand 11 is again given a turn around the joining portion 20 of said cleat, as clearly shown in Figure 5, when the end of the said strand is forced 65 beneath a spring tongue 22 located beneath

the said cleat or clamp 18, and formed by an inward extension of the reinforcing bead 8 at that point.

With the dental floss or other material stretched across the space between the extension in the above manner, it will be readily seen that the same may be easily introduced between the teeth and caused to remove any accumulations therein, the space between the extensions 6 and 7 being ample 75 to permit of a sawing action of the device to draw the strand through the space between the teeth, and the depth of the space between said extensions being ample to accommodate any tooth.

80 After using the device in the above manner, the strand 11 may be detached from the spring tongue 22 in an obvious manner and the same unwound and released from the outer cleat 18, as well as the inner cleat 18, 85 without withdrawing said strand from the alined apertures 21, the used portion being drawn downwardly, as indicated in dotted lines in Figure 1 at 23, and passed beneath an outstanding tongue 24 formed of the metal of the plate, and having its lower edge 25 bevelled to provide a cutting edge by means of which the strand may be severed.

89 The cylindrical box or drum together with the attached floss-supporting arm 4 may be 95 readily grasped by one hand while the cover 13 is turned by the other hand to bring the apertures 16 and 17 into alinement when it is desired to feed out a new length of the floss to be attached to the cleats 18, as described, and the said cover may then be readily turned, as illustrated, to bind the floss between the flanges 2 and 14.

90 From the foregoing it will be seen that a simple, cheaply manufactured and easily 105 operated dental implement has been provided having a receptacle for carrying a spool of dental floss for keeping the same in clean, sanitary condition, and permitting the same to be fed from the casing as needed and threaded and held to provide a stretched portion of the strand in position for use and having means for severing the same when used. Preferably the receptacle, the cover therefor and the spool may correspond 110 with the ordinary devices on the market with such changes therein as are necessary to apply my improvement thereto.

115 What is claimed is:-

120 1. A dental appliance comprising a receptacle for a spool of dental floss, a cover for the same, said cover and receptacle interfitting and provided with openings adapted to aline by turning the cover and receptacle relatively, and means secured to one of said parts and projecting therefrom and constituting a handle by means of which the said parts may be turned, said means having spaced cleats to engage the end of the floss leading from the receptacle.

2. A dental appliance comprising a receptacle for containing a spool of dental floss, a removable cover for the receptacle, the receptacle and cover having interfitting flanges, each flange being provided with an opening for the passage of the dental floss from the spool, and means rigidly secured to the receptacle and adapted to be used in turning the receptacle with reference to the cover, said means having devices for engaging the end of the floss extending from the receptacle, and said means constituting a handle by which the cover may be moved with respect to the receptacle, so as to bring said openings into or out of alinement with each other. 40
3. A dental appliance comprising a receptacle for containing a spool of dental floss, a removable cover for the receptacle, co-acting means embodied in the receptacle and cover for tensioning the floss as it is unwound from the spool, a body portion rigidly secured to the receptacle and having spaced extensions formed thereon, a cleat carried at the terminal of each extension and adapted to clamp the floss from the spool across the space between the extensions and hold the same taut. 45
4. A dental appliance comprising a receptacle for containing a spool of dental floss, a removable cover for the receptacle, co-acting means embodied in the receptacle and cover for tensioning the floss as it is unwound from the spool, a body portion rigidly secured to the receptacle and having spaced extensions formed thereon, a cleat carried at the terminal of each extension and adapted to clamp the floss from the spool across the space between the extensions and hold the same taut. 50
5. A dental appliance comprising a receptacle for containing a spool of dental floss, a removable cover for the receptacle, co-acting means embodied in the receptacle and cover for tensioning the floss as it is unwound from the spool, a body portion rigidly secured to the receptacle and having spaced extensions formed thereon, a cleat carried at the terminal of each extension and adapted to clamp the floss from the spool across the space between the extensions and hold the same taut, and an outwardly projecting spring clamp formed in the body portion adjacent to the outer cleat and adapted to hold the free terminal of the strand of floss. 55
6. A dental appliance comprising a receptacle for containing a spool of dental floss, a removable cover for the receptacle, co-acting means embodied in the receptacle and cover for tensioning the floss as it is unwound from the spool, a body portion rigidly secured to the receptacle and having spaced extensions formed thereon, a cleat carried at the terminal of each extension and adapted to clamp the floss from the spool across the space between the extensions and hold the same taut, and an outwardly projecting, pointed tongue having its lower edge bevelled below the inner cleat to constitute a cutter for severing the used portion of the dental floss. 60

In testimony that I claim the foregoing as my own, I have hereto affixed my signature.

ARTHUR LOW PATTERSON.
